UNITED STATES PATENT OFFICE.

CHARLES LOUIS DOBRICK, OF NEW YORK, N. Y.

DESIGN FOR A BOX.

SPECIFICATION forming part of Design No. 21,840, dated September 6, 1892.

Application filed November 12, 1891. Serial No. 411,740. Term of patent 7 years.

To all whom it may concern:

Be it known that I, CHARLES LOUIS DOBRICK, a citizen of the United States, residing at New York, in the county of New York and State of New York, have invented and produced a new and original Design for Boxes, of which the following is a specification, reference being had to the accompanying drawing, which represents a box showing my design.

10 A in the drawing represents a square box, which has on its front panel an ornamentation consisting of a plate B, that has three inner circles b b' b^2 and is divided by diametrical lines c , so that eight sector-shaped partitions d , eight partitions e , eight partitions f , and eight other partitions g are formed by the

15

outline of the circular plate, the diametrical lines c , and the circles b , b' , and b^2 . In each of the partitions f five playing-cards are arranged, and in each of the sector-shaped partitions d three dice are represented, as shown in the drawing.

What I claim is—

The design for boxes, as described in the specification, and shown in the drawing.

Signed at New York, in the county of New York and State of New York, this 28th day of August, A. D. 1891.

C. LOUIS DOBRICK.
